UNITED STATES PATENT OFFICE.

ANTONIO PAJALIC, OF DEARBORN, MICHIGAN.

AIR WASHER.

1,411,374.

Specification of Letters Patent. Patented Apr. 4, 1922.

Application filed March 3, 1919. Serial No. 280,327.

To all whom it may concern:

Be it known that I, ANTONIO PAJALIC, a citizen of the United States, and a resident of Dearborn, in the county of Wayne, and 5 State of Michigan, have invented certain new and useful Improvements in Air Washers, of which the following is a specification.

My invention is an improvement in air washers, and has for its object to provide 10 a device of the character specified adapted for use with internal combustion engines, wherein a container for water is provided, through which the air must pass, and 15 wherein means is arranged in the container for constraining the air to pass through the water to thoroughly wash the same and remove impurities therefrom when the engine is working, and wherein the constraining 20 means is arranged to permit the air to pass directly into the container above the water to furnish dry atmospheric air to absorb the moisture in the container when the engine is not running.

It is also an object of the invention to 25 provide an air washer for internal combustion engines for automobiles, tractors, and the like, which obviates the necessity of employing closed chambers or floats, 30 which are very sensitive to the disturbance of the water level, as in travelling over uneven surfaces.

In the drawings:

Figure 1 is a vertical section through the 35 purifier;

Figure 2 is a side view showing the position of the parts in dotted lines when the engine is not running;

Figure 3 is a similar view when the engine 40 is working;

Figure 4 is a top plan view.

In the present embodiment of the invention, a container 1 is provided of suitable size and of cylindrical form, consisting of 45 upper and lower sections 1 and 2 which are detachably connected by bolts and nuts, as shown at 3, to form a closed receptacle, and at the center of the bottom of the lower section there is an upwardly extending nipple 50 4, through which the air is adapted to enter the casing.

At one side of the lower section there is an internally threaded drain port 5 which is normally closed by a plug 6 threaded into 55 the port, and near the top of the lower section at the same side there is a filling inlet

7 normally closed by a plug, as shown. The upper section has at its top and at the opposite side from the drain port an outlet 8 with which may be connected a pipe for 60 leading the washed air to the place of utilization, that is, to the carburetor.

A cap 9 is arranged over the nipple, 4, the said cap being of greater diameter than the nipple, and this cap is provided in its top 65 with a port or opening. This cap is of suitable sheet metal, and it has a jacketed petticoat intermediate its ends, the said petticoat consisting of outer and inner walls 10 and 11. The walls of the petticoat are spaced further 70 apart at their connection with the cap wall, and the jacket formed between the walls communicates with the interior of the cap by an annular series of openings 12. It will be noticed that the inner wall 11 extends 75 below the outer wall, at the bottoms of the said walls, and the said inner wall curves outwardly as shown to deflect the air in the same direction. The inner wall has outwardly offset beads 14 for spacing the two 80 walls apart, and rivets 14' are provided in the cap at its lower end for preventing the lower edge of the cap from striking against the nipple 4. The valve 15, which is adapted to close the port 17 in the top of the cap, 85 is normally opened, being supported by a cage 16, and a sheet 18 of gauze is arranged over the opening at the upper end of the port, the valve closing against the lower 90 end.

In operation, when the engine is not running, the parts occupy the dotted-line position of Figure 2, the cap being supported by an air chamber between the cap 9 and the wall 11 in proper relation to the nipple 4, and the valve 15 is open. When the engine is running, the suction will lift the cap and will also lift the valve, the valve closing the port 17 and the air must now pass upwardly through the nipple, downwardly between the cap and the wall of the petticoat into the water, passing again upwardly through the water to the outlet. Thus, the air is thoroughly washed and purified by the water. When the air passes downwardly 100 between the cap and the petticoat, the water will have become displaced from such space by the raising of the cap due to the depression in the container or casing above the water by the suction of the engine. As soon 105 as the proper engine speed is obtained, depression is created above the water level in

the tank, the atmospheric pressure of the air entering the nipple at the bottom of the tank raising the cap and displacing the water between the nipple and the cap and 5 the air will pass out at the lower end of the petticoat through the openings 12 and 13 and bubble up through the water. When the suction stops the valve 15 will drop by gravity to an open position and will remain 10 in this position until the motor is started. As soon as there is suction in the container, the valve 15 closes and the air passes through the water.

No float is needed, since the suction always 15 holds the cap in the proper position, the air chamber between the cap 9 and the wall 11 serving to properly buoy up the cap or washer, the size and weight of the parts being so proportioned as to give a proper 20 balance to permit the rise and fall thereof when the engine or motor is running, and when stopped, the rise and fall of the cap compensating for the variation in the water level, as the water in the container or casing 25 is taken up or consumed in use, it being understood that the water level is normally adjacent to the filling plug 7 and lowers on continued use. The arrangement of the hollow petticoat forces the air to divide evenly. 30 The space beneath the petticoat serves as a reserve for air, and helps the air washer to hold a permanent position when the engine is at work at the proper level and at the proper depth. The inner wall of the petticoat deflects the air outwardly through the 35 water. Rivets 14', it will be noticed, are passed through the cap at its bottom, for engaging the nipple to prevent wear on the cap. When the engine is running the valve 40 15 serves as relief valve opening outwardly when there is undue back pressure in the tank, as, for instance, from pre-ignition.

I claim:

1. An air washer comprising a container 45 adapted to contain water and having a nipple extending upwardly through the bottom thereof above the water level, a cap encircling the nipple and having an opening in its top, a valve for the opening adapted 50 to be closed by the suction of the engine, said cap being lowered when the engine is not running, with the valve open, and being adapted to be lifted and to have the valve closed by the suction through the nipple, 55 said cap having an outwardly extending double wall petticoat near its lower end and having openings between the walls of the petticoat.

2. An air washer comprising a container 60 adapted to contain water and having a nipple extending upwardly through the bottom thereof above the water level, a cap encircling the nipple and having an opening in its top, a valve for the opening and 65 adapted to be closed by the suction of the

engine, said cap being lowered when the engine is not running and being adapted to be lifted by suction through the nipple.

3. An air washer comprising a container adapted to contain water and having a 70 nipple extending upwardly through the bottom thereof above the water level, a cap encircling the nipple, said cap being lowered when the engine is not running and being adapted to be lifted by suction through the 75 nipple when the engine is running, said cap having an outwardly extending double wall petticoat near its lower end and having openings between the walls of the petticoat and spacing heads between said walls. 80

4. An air washer comprising a container adapted to contain water and having a nipple extending upwardly from the bottom thereof above the water level, a cap encircling the nipple, said cap being adapted 85 to be supported or buoyed up by the water in the container or to be lowered in the container when the engine is not running and disposed in close proximity to the bottom of the container when the water is low 90 in the container and being adapted to be lifted by the suction through the nipple, said cap having an outwardly extending double walled skirt near the lower end thereof and the space between said walls communicating 95 with the interior of the cap, the inner wall extending below the outer wall, and means to positively hold said walls spaced apart.

5. In an air washer, the combination with a container adapted to contain water and having a nipple extending upwardly through the bottom thereof for admitting air above the water level in the container; of a cap over the top of the nipple and movable in the water with respect thereto, said cap being normally imperforate at the top when the engine is operated, said cap being open at the bottom and having openings there-through spaced from the lower end thereof, and spaced walls enclosing said openings 100 and extending outwardly and downwardly in spaced relation to the cap to provide an air chamber therebeneath, said cap being adapted to be lifted by the suction to permit the air to pass between said walls and into 105 the water. 110

6. In an air washer, a cap closed at the top and open at the bottom, the lower end of the cap being suitably reinforced, and an outwardly extending double-walled petticoat near the lower end of the cap, said cap having openings between the walls of the petticoat. 120

7. In an air washer, a cap closed at the top and open at the bottom, the lower end 125 of the cap being reinforced with spaced units, and an outwardly extending double-walled petticoat near the lower end of the cap, said cap having openings between the walls of the petticoat, said walls being im- 130

- perforate and the inner wall forming an air chamber with the lower portion of the cap.
8. In a device of the class described a cap closed at the top and open at the bottom, the lower end of the cap being suitably reinforced, and an outwardly extending double-walled petticoat spaced from the lower end of the cap, said cap having openings between the walls of the petticoat and the space therebetween narrowing downwardly, said walls being imperforate and the inner wall forming an air chamber with the lower portion of the cap, the outer wall terminating short of the bottom of the lower wall and both of said walls being spaced from the lower end of the cap.
9. In an air washer of the class described, a cap having a top wall and an open bottom, said cap having peripheral openings spaced from the lower end thereof and an outwardly and downwardly extending double-walled petticoat near the lower end thereof and having the openings between the walls of the petticoat, the lower end of the inner wall being deflected outwardly beneath the lower end of the outer wall, means carried by the lower end of the cap for engaging and holding the same in spaced relation to the usual upwardly extending nipple of the container of the air washer, and an outlet for the air in the cap to discharge the same into the water in the container below the level thereof.
10. A cap of the class described adapted for use with air washers comprising a container having an upwardly extending nipple at the bottom forming an air inlet, said cap having a top wall and an open bottom, said cap having peripheral openings spaced from the lower end thereof and an outwardly and downwardly extending double-walled petticoat near the lower end thereof and having the openings between the walls of the petticoat, the lower end of the cap extending below the lower end of the petticoat and the outer wall of the petticoat terminating short of the lower end of the inner wall and means to slightly space said walls in fixed relation near the lower edge of the outer wall, said petticoat forming an air chamber with the cap closed at the top and open only at the bottom adapted to buoy the cap up over the nipple in the container when the latter is filled with water.
11. An air washer comprising a container adapted to contain water and having a nipple extending upwardly from the bottom thereof for admitting air above the water level, a cap over the top of the nipple for deflecting the air downwardly into and bubble up through the water, and an outlet for the air in the cap to discharge the same into the water in the container below the top level thereof, including an outwardly and downwardly extending passage.

ANTONIO PAJALIC.
